US00D944196S

(12) **United States Design Patent** (10) Patent No.: **US D944,196 S**
(45) Date of Patent: **** Feb. 22, 2022**

(54) **POWER BANK**

(71) Applicant: **LUXSHARE PRECISION INDUSTRY CO., LTD.**, Shenzhen (CN)

(72) Inventors: **Yun Feng**, New Territories (HK); **Guo-Qin Huang**, New Territories (HK); **Qi-Jun Yin**, New Territories (HK); **Shuang-Shuang Chen**, New Territories (HK)

(73) Assignee: **LUXSHARE PRECISION INDUSTRY CO., LTD.**, Shenzhen (CN)

(**) Term: **15 Years**

(21) Appl. No.: **29/749,051**

(22) Filed: **Sep. 2, 2020**

(30) **Foreign Application Priority Data**

Mar. 19, 2020 (CN) 202030094046.0

(57) **CLAIM**

The ornamental design for a power bank, as shown and described.

DESCRIPTION

FIG. 1 is a top perspective view of a power bank showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a perspective schematic view of a power bank illustrating in one using position in accordance with the present design.

1 Claim, 6 Drawing Sheets
